UNITED STATES PATENT OFFICE.

MEREDITH LEITCH, DECEASED, LATE OF POUGHKEEPSIE, NEW YORK; BY LUCY BURRUSS LEITCH, ADMINISTRATRIX, OF MONTGOMERY, ALABAMA, ASSIGNOR TO THE DE LAVAL SEPARATOR COMPANY, OF NEW YORK, N. Y., A CORPORATION OF NEW JERSEY.

DRIVING MEANS FOR CENTRIFUGAL BOWLS.

Application filed December 6, 1920. Serial No. 428,449.

To all whom it may concern:

Be it known that MEREDITH LEITCH, deceased, late a citizen of the United States, residing at Poughkeepsie, county of 5 Dutchess, and State of New York, did in his lifetime invent certain new and useful Improvements in Driving Means for Centrifugal Bowls, of which the following is a full, clear, and exact description, reference 10 being had to the accompanying drawings, which form a part of this specification.

This invention relates to the mounting of centrifugal bowls on, and driving them by, the spindles of their machines.

15 If there is any deviation from true running of the neck of a bowl either because the bowl is eccentric with the spindle or because it is out of alignment with the spindle, the ratio between the cream and the skim milk 20 will change and hence change the density of the cream.

The most common means for driving a centrifugal bowl is by cutting away a portion of the upper end of the spindle to form 25 a member which, in combination with a mating member in the bowl, acts as a positive jaw clutch. This method is open to two serious objections. When the bowl is placed on the spindle it must be carefully turned

30 around until the clutch engages, and because of unavoidable irregularities in manufacture, the clutch has a tendency to force the bowl out of concentricity with the spindle and cause rough running. This latter is a 35 condition that increases with the wear resultant from long use. Forms of clutch have been invented which theoretically equalize the drive, but in practice they have been found to eventually cause eccentricity.

40 A less common means for driving the bowl is to provide a long taper on the upper portion of the spindle and provide in the bowl a socket of a similar taper into which the spindle wedges tightly. This 45 method is objectionable because, when the bowl is taken out of the machine for washing, the spindle must be taken with it and then driven out of the bowl. The spindle is liable to be sprung or have the bearings 50 marred during this operation.

The object of the invention is to provide for centrifugal bowls a mounting and driving means wherein there will be no possibility of eccentricity of the bowl to the spin-

dle or of inclination of the axis of the bowl 55 to the axis of the spindle and in which there will be no difficulty in lifting the bowl off the spindle, which may remain in the machine. Another object is to provide a mounting means in which wear will cause no 60 deterioration of the fit between the bowl and the spindle. Another object of the invention is to avoid the use of clutches or any other structural complications likely to cause eccentricity and rough running and to 65 provide a construction of maximum simplicity. A further object of the invention is to insure the provision and maintenance of an efficient supporting and driving connection between the spindle and bowl without 70 the necessity of constructing such driving connection with ideal accuracy; so that either unavoidable irregularities in manufacture on the one hand, or an intentional, but easily obtainable, departure from exact 75 fit on the other hand, will not affect the efficiency and durability of the supporting and driving connection: thus providing a construction which can be manufactured without high skill or extreme care and hence one 80 that will be comparatively inexpensive to make.

Bowl supporting and driving means accomplishing all the foregoing objects except the last has been devised by the inventor 85 and may be utilized, but not indispensably, as an element of the present invention. Such objects are accomplished by providing the upper end of the spindle with a taper in rigid concentric relation therewith, and by 90 providing in the bowl a frustro-conical socket adapted to said taper, and by inclining the engaging walls of the taper and socket at so great an angle to the axis of rotation of the bowl that the spindle will not 95 seize therein and yet at so small an angle with said axis of rotation that the weight of the bowl will cause sufficient friction to drive the bowl. In specifying that the spindle shall not "seize" in the bowl socket, the 100 word "seize" is used in the relative sense in which it is used in the art, namely: to express a wedging action between the spindle and bowl socket such that the spindle must be forcibly driven out of the bowl, as distinguished from a case where, with only relatively slight resistance to movement of the spindle with the bowl, the bowl may be easily 105

lifted off the spindle. By a non-seizing angle is meant any angle so broad that after placing a bowl on its spindle, the resistance to removal of the bowl will be less than twice 5 the weight of the bowl. In specifying that the spindle shall be provided with a taper, it is meant to exclude a construction wherein a tapered member might be mounted on the spindle in non-rigid relation therewith 10 and which might be held on the spindle by a pin-and-slot connection or other connection, which, inherently, cannot be made so nearly perfect that it will be necessarily concentric with the axis of the spindle, or 15 which, if assumed to be originally concentric, cannot maintain that concentricity in operation. In other words, the formation is contemplated of a taper which shall be in rigid relation with the spindle, preferably 20 on the spindle itself, thereby avoiding all possibility of the eccentricity that it is sought to prevent. The narrow range of angularity above specified is capable of exact calculation by the skilled artisan or engineer, as applied to any given weight of 25 bowls. For example, in very small light bowls the included angle of the cone may be as little as twelve degrees while for large heavy bowls it may need to be as wide as 30 twenty degrees.

While this construction is operative, both technically and commercially, and is, perhaps, an ideal construction, it is open to the objection that great care and skill are required in insure accuracy in the formation of both the socket and the cone, an exact correspondence of the angles of taper of both members to the axis of rotation being practically necessary, or at least highly desirable, 35 to insure proper operation throughout the life of the structure. The inventor has discovered that if a guide, or centering or steadyng portion, is provided at a substantial distance from the conical support, it 40 is not necessary that the angles of the cone and socket shall be the same. In view of the difficulty and expense of insuring an exact correspondence, it is desirable to deliberately make the angle of the socket slightly 45 less than that of the cone, so that initial contact will be toward the lower end of the cone at or near its largest diameter, thus giving a driving effect as great as possible. The angle of the socket may be actually 50 greater than that of the cone, but this is undesirable because the initial contact will then be at the smallest diameter of the cone, thus securing a minimum driving effect. Such a condition may actually be produced 55 if it is sought to make the angles exactly coincident, wherefore it is desirable, as above stated, to purposely make the angle of the socket slightly less than that of the cone. It is understood, however, that even if the angles of the two engaging members corre-

spond, or it is sought to make them correspond, the provision of the additional spaced apart centering or steadyng portion is of substantial advantage. As a matter of practical manufacture, it is desirable that the included shall vary from a fraction of one degree to as much as several degrees less than that of the cone. This makes the manufacture comparatively easy and cheap. When in use a small portion of the lower 75 part of the socket will soon exactly fit the cone.

In the accompanying drawings which show an embodiment of this invention:

Fig. 1 shows, partially in cross-section, a 80 centrifugal bowl, part of the spindle on which it is mounted, and part of the frame of the machine.

Fig. 2 shows, on a larger scale, the upper 85 part of the spindle, and the adjacent parts of the bowl.

a is a bowl spindle supported in the usual bearings. It may be driven by the usual gearing. At the upper end of the spindle is a portion *b* tapered at an angle only blunt enough to prevent seizing. Below the taper portion the spindle has a cylindrical portion *c* concentric with the taper. At the bottom of the bowl *d* is a bushing *e* closely fitting the cylindrical portion *c* of the spindle, forming a bowl centering and steadyng portion. At a substantial distance above the bushing *e* is a socket *f*, having a taper slightly less than that of the spindle. As can be seen by reference to the drawings, there is a space around the spindle between its receiving portion in the bowl and between the bushing *e* and the socket *f*, so as to insure engagement of the spindle at the tapered portion and at the steadyng portion. *g* is a part of the frame of the machine. *h* is a stop screw which projects inside the frame above a limit *i* on the spindle.

In ordinary operation the spindle *a* remains in the frame at all times. When it is desired to use the machine, the bowl is placed over the spindle, and its own weight carries it down, guided by the bushing, till the lower part of the socket engages the taper. When it is desired to wash the bowl, a quick upward pull will lift the bowl and spindle until the collar *i* comes in contact with the screw *h*, when the spindle will stop and the bowl will be disengaged and may be carried to any convenient place for washing.

Having now fully described this invention, what is claimed and desired to be protected by Letters Patent is:—

1. Driving means for a centrifugal bowl comprising a centrally disposed spindle socket in the bowl, said socket having a conically tapered wall, and a bowl spindle having a conically tapered portion to en-

gage the conically tapered socket, the angles of said tapers to the axis of rotation being nearly, but not precisely, the same, the tapered faces of the engaging members 5 adapted to contact along a circumferential line so that in use wear will provide a circumferential zone of driving contact of appreciable area.

2. A centrifugal machine having a bowl 10 with a spindle socket therein, said socket having a conically tapered wall, a spindle for the bowl having a conically tapered portion to engage the tapered socket, the angle of taper of the spindle to the axis of rotation being close to, but measurably greater than, the angle of taper to the 15 socket of the axis of rotation.

3. Driving means for a centrifugal bowl comprising a centrally disposed conically 20 tapered spindle socket in the bowl and a bowl spindle having a conically tapered portion, the angle of taper of the spindle to the axis of rotation closely approximating, but being slightly greater than, the 25 angle of taper of the socket to the axis of rotation, whereby an initial circumferential driving contact between the spindle and cone may be provided at larger diameter portions of spindle and cone.

30 4. A centrifugal machine having a bowl with a centrally disposed spindle socket having an upper conical portion and a lower steadyng portion, and a spindle adapted for engagement with the lower 35 steadyng portion of the socket and provided with a conical portion for engagement with the conical seating portion of the socket, the conical portion of the spindle having a taper of measurably greater angle 40 to the axis of rotation than the taper of the conical portion of the socket.

5. A centrifugal machine having a bowl 45 with a centrally disposed spindle socket therein, said socket having a conical seating portion and a cylindrical steadyng portion, and a spindle having a cylindrical portion for engagement with the cylindrical steadyng portion of the socket and a conical portion for engagement with the conical seating 50 portion of the socket, the conical portions of the spindle and socket having closely approximating but different angles of taper and being in circumferential driving contact at a substantial distance from 55 the axes of rotation.

6. A centrifugal machine having a bowl 60 with a centrally disposed spindle socket therein, said socket having a conical seating portion and a cylindrical steadyng portion, and a spindle having a cylindrical portion for engagement with the cylindrical steadyng portion of the socket and a conical portion for engagement with the conical seating 65 portion of the socket, the conical portion of the spindle having a taper of measurably

greater angle to the axis of rotation than the conical portion of the socket.

7. A centrifugal machine having a bowl 70 with a centrally disposed conical spindle socket therein and a spindle having a conical portion for engagement with said socket and having an angle of taper to the axis of rotation measurably greater than the angle of taper of the socket so as to insure driving contact throughout a relatively large 75 circumference; the bowl having also, spaced from said socket, a cylindrical steadyng portion, and the spindle having a cylindrical portion engaging said cylindrical steadyng portion of the bowl but clear of the bowl 80 between said steadyng portion and socket.

8. A centrifugal machine comprising a vertical bowl and a vertical rotatable spindle for supporting and rotating the bowl, the bowl having a conically tapered socket, 85 and at a substantial distance below it a cylindrically bored guide bushing, the spindle having rigid therewith a conical socket engaging member of a greater taper than the socket, providing a friction clutch surface 90 engaging the lower part of the socket and below the cone a cylindrical surface adapted to engage the bushing in the bowl, the angle of the cone to the axis of rotation being sharp enough to insure sufficient friction, by reason of the weight of the bowl, to cause the bowl to be held in driving engagement with the spindle but great enough to prevent seizure and thus permit the bowl 95 to be readily lifted off the spindle when vertical movement is resisted.

9. A centrifugal machine comprising a rotatable bowl and a vertical rotatable spindle for supporting and rotating the bowl, the bowl having a tapered socket and the spindle having rigid therewith a conical socket engaging member providing a friction clutch surface engaging the socket, the angle of the socket and cone to the axis of rotation being sharp enough to insure sufficient friction, by reason of the weight of the bowl, to cause the bowl to be held in driving engagement with the spindle but great enough to prevent seizure and thus permit the bowl to be readily lifted off the shaft when vertical movement is resisted, the opposing faces of the socket and socket-engaging member to the axis of rotation being nearly, but not precisely, the same and adapted to contact along a circumferential line so that in use wear will provide a circumferential zone of driving contact of substantial area.

10. A centrifugal machine comprising a 125 rotatable bowl and a vertical rotatable spindle for supporting and rotating the bowl, the bowl having a tapered socket and the spindle having rigid therewith a conical socket engaging member providing a friction clutch surface engaging the socket,

the angle of the socket and cone to the axis of rotation being sharp enough to insure sufficient friction, by reason of the weight of the bowl, to cause the bowl to be held in driving engagement with the spindle but great enough to prevent seizure and thus permit the bowl to be readily lifted off the shaft when vertical movement is resisted. the angle of taper to the axis of rotation of the opposing face of the socket-engaging member closely approximating, but being slightly greater than, the angle of taper to the axis of rotation of the socket, where

by an initial circumferential driving contact between the spindle and bowl socket 15 may be provided at larger diameter portions of the opposing faces and facilitate the provision, due to wear in use, of a circumferential zone of driving contact of substantial area.

In testimony of which invention, I have hereunto set my hand, at Montgomery, on this 27 day of November, 1920.

LUCY BURRUSS LEITCH.
